(57) **CLAIM**

The ornamental design for table-top washing machine, as
shown and described.

DESCRIPTION

FIG. 1 is a front view of the table-top washing machine of
this Design;

FIG. 2 is a right side view thereof;

FIG. 3 is a plan view thereof;

FIG. 4 is a bottom view thereof;

FIG. 5 is a back view thereof;

FIG. 6 is a left side view thereof;

FIG. 7 is a perspective view;

FIG. 8 is a perspective view with cap removed;

FIG. 9 is a vertical sectional view;

FIG. 10 is a view showing the part names; and,

FIG. 11 is another view showing the part names.
